Primary Examiner—Stella Reid*Attorney, Agent, or Firm*—Richard C. Litman[57] **CLAIM**

The ornamental design for a kit for a combination plush toy and teether, as shown and described.

DESCRIPTION

FIG. 1 is a front and right side perspective view of a kit for a combination plush toy and teether, showing my new design, in assembled condition;

FIG. 2 is a front elevational view thereof, in disassembled condition;

FIG. 3 is a top plan view thereof;

FIG. 4 is a rear elevational view thereof;

FIG. 5 is a bottom plan view thereof; and,

FIG. 6 is a left side elevational view with the right side being a mirror image thereof.
